UNITED STATES PATENT OFFICE.

RUDOLPH F. STEHLIK, OF CHICAGO, ILLINOIS, ASSIGNEE, BY MESNE ASSIGNMENTS, TO AUTOMATIC ELECTRIC INC., OF CHICAGO, ILLINOIS, A CORPORATION OF DELAWARE.

IMPULSE SENDER.

Application filed June 9, 1924, Serial No. 718,683. Renewed December 29, 1926.

The present invention relates in general to impulse senders but is concerned more particularly with impulse senders used in telephone systems and more especially those 5 which employ a progressively movable switch mechanism to count the impulses as they are sent or transmitted.

The main object is the production of new and improved circuit arrangements whereby 10 the counting switch of a sender is provided with a plurality of normal positions to avoid the necessity of rotating over all the remaining positions when a series of impulses comprising only a small number of impulses is 15 transmitted. For example, impulse senders are ordinarily designed to send out a maximum of ten impulses and have, in addition to one normal position and one pick-up position, ten sending positions. Now in case a 20 series of impulses comprising only three impulses, for example, is transmitted, it is necessary, at the end of the series, to advance the sending switch through its remaining seven positions before its normal position is 25 reached.

In order to cut down this large amount of wasted movement, which is the cause of a large amount of wear and tear on the switch mechanism itself and is also the cause of 30 wasted time between successive series of impulses, a novel circuit arrangement has been provided which allows for a second normal position at which the sending mechanism may be stopped at a half way point. Now, 35 in order to prevent the sending mechanism from being out of step when it is started from this second normal position, it is provided with a second control wiper which is automatically connected up and used instead 40 of the normal control wiper when the switch is started from its intermediate normal position.

Although senders of the above type may 45 be used for any one of a number of purposes and in connection with any one of a number of devices, it has been chosen to illustrate the sender in connection with a so-called "director" which is employed in a multi-office automatic telephone system primarily to promote trunking efficiency by permitting calls to all offices in the same locality to be handled over the same group of trunks regardless of their numerical designation. These directors are used to register 55 the office digits of a number and to retrans-

mit the proper code to trunk the call to the desired office in accordance with the most economical trunking arrangement and to register and retransmit unchanged the four subscriber digits of a number. 60

Although the director as a whole does not form any part of this invention, but is used merely to illustrate one use for the new and improved sender, it is, nevertheless, an object of the invention to combine the new and improved sender with the remaining part of the director so that the entire director functions as a unitary organization. 65

Referring now to the drawings comprising 70 Figs. 1-5, inclusive, they show by means of the usual circuit diagrams, a sufficient amount of apparatus in a system embodying the principles of invention to enable the invention to be understood and its utility appreciated. 75

Fig. 1 shows the substation A of which the associated line terminates at the exchange in the line switch C, which has access through the trunk circuit TC to the first selector D. This drawing shows also the director selector DS. 80

Figs. 2-5, inclusive, show a director which is one of the group accessible to the director selector DS, Fig. 1. The portion of the director shown in Fig. 2 comprises the sequence switches S and S' which are used respectively to control the registration and the retransmission of the impulses; the portion of the director shown in Fig. 3 comprises the new and improved sender which sends out 85 the correct number of impulses for each digit, starting from either of its two normal positions impartially; the portion of the director shown in Fig. 4 comprises the office register OR and the intermediate distributing frame IDF by means of which the office codes may be readily changed; and the portion of the director shown in Fig. 5 comprises the digit registers DR¹-DR⁴, inclusive, which are used to register the four subscriber digits in a number. 90

Regarding the equipment involved in the present disclosure, it may be stated that the substation A, Fig. 1, is of the usual automatic type; the line switch C, Fig. 1, together with the director selector DS, the sequence switch S', Fig. 2, and the sending switch SS, Fig. 3, is of the well known rotary type of switch in which the wipers are moved in a forward direction only and 100

are advanced upon the back stroke of the stepping magnet rather than upon the front stroke; the selector D, Fig. 1, together with the office register OR, Fig. 4, is an automatic switch of the well known vertical and rotary type and its bank contacts are accordingly arranged in horizontal rows or levels; and the sequence switch S, Fig. 2, together with the digit registers DR¹-DR⁴, inclusive, Fig. 5, is of a simple type of switch having wipers which are advanced in a forward direction by the stepping magnet 105 and which are restored to normal by the release magnet 106 under the control of the contacts 107 which close when the wipers 108 and 109 are first moved from their normal position and which open again when the wipers are subsequently restored to their normal position.

A detailed description of the operation of the apparatus shown will now be given. For this purpose it will be assumed that the subscriber at substation A, desiring to make a call, removes his receiver. When this occurs, a circuit is closed over line conductors 11 and 12 for line relay 15 of the line switch C, whereupon line relay 15 energizes; places ground on private normal conductor 13 at armature 23, thereby making the calling line busy immediately and closing a circuit through switching relay 14 and stepping magnet 16 in series; and at armature 24 connects test wiper 21 to the junction of switching relay 14 and stepping magnet 16.

From this point the operation depends upon whether the trunk terminating in the bank contacts upon which the wipers of the line switch are standing is busy or idle. Assuming first that the trunk is idle, switching relay 14 energizes immediately, seizing the trunk.

Assuming now that the trunk upon which the wipers of the line switch are standing is busy, switching relay 14 is short circuited by the ground potential encountered on the busy test contact by test wiper 21 and does not energize. Stepping magnet 16, which interrupts its own circuit, is operated from this same ground potential through test wiper 21 and advances the wipers 20-22, inclusive, step by step in search of an idle trunk. When an idle trunk is reached, which trunk, it will be assumed, is the one comprising conductors 25-27, inclusive, there is no ground potential encountered upon the test contact thereof by test wiper 21, and switching relay 14, being no longer short circuited, energizes. Stepping magnet 16, however, does not energize at this time, on account of the high resistance of switching relay 14. Upon energizing, switching relay 14 disconnects test wiper 21 from the junction of its own winding and that of stepping magnet 16 and connects it to the grounded private normal conductor 13 at armature 18,

thereby making the seized trunk busy immediately, and at armatures 17 and 19 disconnects the line conductors 11 and 12 from the windings of line relay 15 and ground, and extends them by way of wipers 20 and 22, the bank contacts upon which they are standing, conductors 25 and 27, and the resting contacts and armatures 39 and 41 to the windings of the double wound line relay 31 of the trunk circuit TC. Line relay 31 now energizes over the calling line and closes at armature 34 a circuit for release relay 32, whereupon release relay 32 energizes and places ground upon release trunk conductor 26, at armature 36 thereby completing the usual holding circuit for switching relay 14 of the line switch C before the slow acting line relay 15 has had time to deenergize.

As a further result of the energization of release relay 32, it closes at armature 37 a circuit for switching relay 81 and stepping magnet 82 of the director selector DS in series, and at armature 38 connects test wiper 89 to the junction of the said switching relay and stepping magnet. Accordingly, the director selector DS operates in the same manner as already explained in connection with the line switch C to select an idle director. Assuming that the director reached by way of conductors 91-94, inclusive, is the first one found to be idle, the wipers 87-90, inclusive, are rotated and stopped in engagement with the bank contacts in which the said conductors 91-94, inclusive, terminate, whereupon switching relay 81 energizes and grounds test wiper 89 at armature 85, thereby making the seized director busy immediately. As a further result of the energization of switching relay 81, it prepares the operating and switching circuit at armature 86; and at armatures 83 and 84 connects up wipers 87 and 88, thereby placing a closed bridge across conductors 42 and 44 of the selector D. This closed bridge includes conductors 91 and 92, and armature 208 and its resting contact of relay 202, Fig. 3, and contacts 233 of the sending switch SS in multiple. Responsive to the closure of this bridge, line relay 51 of the selector D energizes and closes a circuit for release relay 52 at armature 62, whereupon release relay 52 energizes also, preparing the selector for operation in the usual manner.

In the director, the holding relay 201, Fig. 3, is energized over test conductor 93 responsive to the latter being grounded through wiper 89 of the director selector DS, and at armatures 206 and 207 opens the two release circuits of the director.

When the calling subscriber manipulates his calling device in accordance with the first digit in the desired number, the circuit of line relay 31 of the trunk circuit TC is opened a corresponding number of times. Upon each of the resulting deenergizations

of line relay 31, it closes at armature 35 a circuit for the vertical magnet 301 of the office register OR, Fig. 4, as follows: From ground by way of the resting contact and armature 35 of the line relay 31, armature 86 and its working contact, wiper 90, conductor 94, slow acting series relay 101, Fig. 2, wiper 109 of the sequence switch S, the vertical magnet operating conductor 115, and vertical magnet 301 of the office register OR to battery. By the operation of vertical magnet 301, the wipers 304-307, inclusive, of the office register OR are raised step by step and come to rest opposite the desired level of bank contacts. Relay 101, Fig. 2, is energized in series with the vertical magnet and, being slow acting, maintains its armature attracted throughout the series of impulses. Upon energizing, relay 101 closes at armature 103 a circuit for the slow acting relay 102 which thereupon energizes and prepares at armature 104 a circuit for stepping magnet 105 of the sequence switch S.

At the end of the series of impulses transmitted to the vertical magnet of the office register, slow acting series relay 101 deenergizes and closes at armature 103 the circuit of stepping magnet 105 of the sequence switch S, whereupon the stepping magnet 105 energizes and advances the wipers 108 and 109 into engagement with the second set of bank contacts. A moment later, the slow acting relay 102, whose circuit is opened by armature 103, deenergizes and opens the circuit of magnet 105 at armature 104.

The impulse distributing wiper 109 of the sequence switch S is now in engagement with the bank contact associated with the rotary magnet 302 of the office register OR. Accordingly, when the calling subscriber manipulates his calling device in accordance with the second digit in the desired number, the resulting series of impulses is transmitted over the circuit above traced to the said wiper 109 of the sequence switch S and thence by way of the second associated bank contact, and conductor 116 to rotary magnet 302. By the operation of rotary magnet 302, the wipers 304-307, inclusive, of the office register OR are rotated into engagement with the desired set of bank contacts in the level selected by the first digit, which contacts, it will be assumed, are the contacts 308-311, inclusive.

At the end of this second series of impulses, the wipers 108 and 109 of the sequence switch S are advanced in the hereinbefore described manner, and wiper 108, upon coming into engagement with the third associated bank contact, connects the interrupter 114 to conductor 110, thereby starting the sender in a manner to be pointed out hereinafter.

When the first subscriber digit is dialled,

the stepping magnet 401 of the first digit register DR¹, Fig. 5, is operated through wiper 109 of the sequence switch S, Fig. 2, and over conductor 121 and advances the wiper 404 into engagement with the bank contact corresponding to the digit dialled. In the same way, responsive to the second, third, and fourth subscriber digits, the digit registers DR², DR³, and DR⁴, respectively, are operated over conductors 122, 123 and 124, respectively, and each advances its wiper into engagement with the bank contact corresponding to the number of impulses received.

Returning now to the point at which wiper 108 of the sequence switch S connected up the interrupter 114 to the conductor 110, the stepping magnet 231 of the sending switch SS is thereafter operated through the resting contact and armature 213 under the control of interrupter 114. Upon the first energization of stepping magnet 231, the associated armature is attracted and moves the pawl into engagement with the next notch in the wiper driving ratchet wheel but does not move the wipers 234-237, inclusive. The armature of stepping magnet 231 also opens the sending contacts 233, but the bridge across conductors 91 and 92 is not opened at this time owing to the fact that the contacts 233 are shunted at the resting contact and armature 208 of pick-up relay 202.

Upon the subsequent deenergization of stepping magnet 231, the wipers 234-237, inclusive, are advanced into engagement with the next set of bank contacts. When this occurs, wiper 235 opens the initial circuit of relay 205 which was formerly closed through wiper 235 and the resting contact and armature 209, leaving relay 205 locked up through armature 219 and its working contact. Accordingly, relay 205 maintains the stop wiper 236 (which is the one to be used when the sender is started from the normal position shown) connected with stop relay 203 at armature 220, and maintains contact 238 in the bank of wiper 234 grounded at armature 218 so as to prevent wiper 234 from losing ground in case it rotates over contact 238 during the transmission of the series of impulses.

As a further result of the advance of the wipers of the sending switch, wiper 234 engages a grounded contact, whereupon pick-up relay 202 energizes and removes at armature 208 the shunt from around contacts 233 of the sending switch. Relay 202 also places an auxiliary ground on conductor 93 at armature 209 so as to maintain the director busy until the sender has completed its operation in case the calling subscriber should hang up prematurely. As a further result of the energization of pick-up relay 202, it closes at armature 210 a circuit over conductor 118 for the stepping magnet 111 of

the sequence switch S', whereupon stepping magnet 111 energizes preparatory to advancing the associated wipers.

With the shunt removed from around the sending contacts 233 of the sending switch SS, each of the subsequent energizations of stepping magnet 231 results in an opening of the bridge across conductors 91 and 92, the wipers of the sending switch being advanced in the usual manner upon each subsequent deenergization. Now, upon referring to Fig. 4 it will be noted that the first wiper 304 of the office register OR is in engagement with the bank contact 308, which is cross-connected on the intermediate distributing frame IDF by means of the jumper 312 to the third impulse stop conductor 3. Accordingly, the first code digit to be transmitted is the code digit 3, and, when three interruptions have been produced in the bridge across conductors 91 and 92, the stop wiper 236 of the sending switch is advanced into engagement with the bank contact in which the third impulse stop conductor 3 terminates, and stop relay 203 energizes over the following circuit: From ground by way of the stop conductor control wiper 113 of the sending control sequence switch S', Fig. 2, the first associated bank contact, the first code digit stop conductor 131, wiper 304 of the office register OR, bank contact 308, jumper 312 of the intermediate distributing frame IDF, the third impulse stop conductor 3, the corresponding contact in the bank of wiper 236 of the sending switch SS, Fig. 3, armature 220 and its working contact, and stop relay 203 to battery. Upon the closure of this circuit, stop relay 203 energizes and shunts the sending contacts 233 at armature 211, thereby terminating the transmission of impulses. Relay 203 also opens the circuit of stepping magnet 111 of the sequence switch S' and closes a locking circuit for itself at armature 214; shifts at armature 213 the circuit of stepping magnet 231 from the interrupter lead 110 to wiper 234 through the interrupter contacts 232; and at armature 212 opens the locking circuit of relay 205, incidentally removing the ground potential from bank contact 238, whereupon relay 205 deenergizes.

As a result of the opening of the circuit of stepping magnet 111 of the sequence switch S' at armature 214, stepping magnet 111 de-energizes and advances the wipers 113 and 114 into engagement with the second set of bank contacts, and as a result of the shifting of the circuit of stepping magnet 231 of the sending switch SS at armature 213, stepping magnet 231 is operated through wiper 234 and interrupter contacts 232 and advances its wipers step by step until wiper 234 engages the bank contact 238, which is at this time ungrounded. The wipers of the sending switch SS are now at their intermediate nor-

mal position and the circuit of pick-up relay 202 is open on account of the fact that wiper 234 is in engagement with an ungrounded bank contact. Relay 202, however, being slow acting, does not deenergize immediately. 70

In the selector D, Fig. 1, as a result of each of the three interruptions produced in the bridge across conductors 91 and 92 in the director, line relay 51 deenergizes and closes at armature 62 a circuit through armature 64 and its working contact and series relay 53 for vertical magnet 61. By the operation of vertical magnet 61, the wipers 72-74, inclusive, are raised step by step and come to rest opposite the third level of bank contacts. Relay 53 is energized in series with vertical magnet 61 and, being slow acting, maintains its armature 65 attracted throughout the vertical movement. Upon the closure of the off normal contacts, a circuit is completed from the grounded release trunk conductor 43, through armature 65 and its working contact, and through the interrupter contacts 59 of rotary magnet 58 for stepping relay 54, which thereupon energizes and closes a locking circuit for itself at armature 66, and prepares a circuit for rotary magnet 58 at armature 67. 80

At the end of the vertical movement, the slow acting series relay 53 deenergizes and completes the circuit of rotary magnet 58 at armature 65, whereupon rotary magnet 58 energizes and advances the wipers 72-74, inclusive, into engagement with the first set of bank contacts in the selected level, and, near the end of its stroke, opens the circuit of the stepping relay 54 at its interrupter contacts 59. Stepping relay 54 thereupon falls back and opens the circuit of rotary magnet 58 at armature 67, whereupon rotary magnet 58 deenergizes and closes its interrupter contacts 59 again. 95

From this point on, the operation depends upon whether the trunk terminating in the first set of bank contacts is busy or idle. 100 If it is idle, switching relay 55 energizes, seizing the trunk. Assuming, however, that the trunk is busy, switching relay 55 is short circuited by the ground potential encountered upon the busy test contact by test wiper 73, and stepping relay 54 energizes through test wiper 73 and again completes the circuit of rotary magnet 58 at armature 67, whereupon rotary magnet 58 energizes also and advances the wipers into engagement with the second set of bank contacts. 115

This alternate operation of stepping relay 54 and rotary magnet 58 continues as described until an idle trunk is reached, which trunk, it may be assumed, is the one comprising conductors 75-77, inclusive. When this idle trunk is reached, switching relay 55, being no longer short circuited, energizes from ground on the grounded release trunk conductor 43 and in series with off normal 120

contacts 60, interrupter contacts 59, and stepping relay 54, but stepping relay 54 is not operatively energized at this time on account of the high resistance of switching relay 55. Upon energizing, switching relay 55 opens the test circuit and prepares the usual holding circuit at armature 69; disconnects ground from armature 62 of the line relay 51 at armature 70, thereby opening the circuit of the slow acting release relay 52; and at armatures 68 and 71 disconnects conductors 42 and 44 from the windings of the line relay 51 and extends them by way of wipers 72 and 74, the bank contacts with which they are in engagement, and conductors 75 and 77 to the line relay of the selector switch associated with the seized trunk. The line and release relays (not shown) of the seized selector now energize 20 and the latter places ground on release trunk conductor 76, thereby grounding the release trunk conductor 43 of the selector D through wiper 73 and armature 69 and its working contact to maintain the holding circuit closed 25 after the slow acting release relay 52 of the selector D has deenergized and also after the release relay 32 of the trunk circuit TC has deenergized, as it does subsequently.

In the director, the slow acting pick-up relay 202 falls back at the end of the interval for which it is adjusted and opens the circuit of slow acting stop relay 203 at armature 210. Stop relay 203 also maintains its armature attracted for an interval after its circuit is opened, at the end of which it will fall back and start the sender again as will be pointed out. The interval required for the relays 202 and 203 to fall back one after the other is made use of by the selector D to perform the change-over and trunk-hunting operations above described. As a further result of the deenergization of the slow acting pick-up relay 202, it replaces ground on wiper 235 of the sending switch SS, thereby completing a circuit through bank contact 239 for relay 204. Relay 204 thereupon energizes and prepares a locking circuit for itself at armature 216, and at armature 217 connects up the stop wiper 237 with the stop relay 203.

At the end of the time for which it is adjusted, relay 203 deenergizes and closes at armature 212 a locking circuit through the working contact and armature 216 for relay 204, at the same time connecting ground through armature 215 and its working contact to the first contact in the bank of wiper 234 so as to prevent the said wiper 234 from losing ground in case it passes over such contact during the transmission of the next digit. As a further result of the deenergization of relay 203, it again connects stepping magnet 231 of the sequence switch SS to the interrupter 114, Fig. 2, through conductor 110, thereby starting the sender for

the transmission of the second and last code digit. Upon the first energization of stepping magnet 231, the associated armature is attracted and the pawl is moved into engagement with the next notch in the wiper driving ratchet wheel, and, upon the subsequent deenergization, the wipers 234-237, inclusive, are advanced one step and wiper 234 engages a grounded contact, thereby closing a circuit for pick-up relay 202. Pick-up relay 202 accordingly energizes; opens the initial circuit of relay 204 at armature 209, leaving the said relay 204 energized through its locking circuit which includes armatures 212 and 216; closes a circuit at armature 210 and over conductor 118 for the stepping magnet 111 of the sequence switch S'; and at armature 208 removes the shunt from around the sending contacts 233 of the sending switch SS. Accordingly, upon each of the following energizations of stepping magnet 231, the bridge across conductors 91 and 92 is opened at the sending contacts 233.

At the end of the fifth interruption produced in the bridge across conductors 91 and 92 by stepping magnet 231, stepping magnet 231 deenergizes and closes the bridge again and again advances the wipers 234-237, inclusive. Wiper 237, at this time engages the bank contact in which the fifth impulse stop conductor 5 terminates, thereby closing a circuit for stop relay 203 as follows: From ground by way of stop conductor control wiper 113 of the sequence switch S', Fig. 2, the second associated bank contact, the second code digit stop conductor 132, wiper 305 of the office register OR, bank contact 309, jumper 313, the fifth impulse stop conductor 5, the associated contact in the bank of wiper 237 of the switch SS, armature 217 and its working contact, and stop relay 203 to battery. Upon energizing, stop relay 203 opens at armature 214 the circuit of the stepping magnet 111 of the sequence switch S' and closes a locking circuit for itself; places a shunt around the interrupter contacts 233 of the sending switch SS at armature 211; and at armature 212 opens the locking circuit of relay 204, whereupon relay 204 deenergizes. As a further result of the energization of stop relay 203, it disconnects stepping magnet 231 from the interrupter lead 110 at armature 213 and connects it through the interrupter contacts 232 to the wiper 234. However, the wipers of the sending switch are not advanced at this time, owing to the fact that they are now in one of their normal positions, ground being removed from the first contact in the bank of wiper 234.

Responsive to the transmission of the second code digit 5, the selector switch associated with the trunk seized by the selector D, Fig. 1, operates in the usual manner to

raise its wipers to the desired level and select a trunk leading to the called office.

After the usual interval, relays 202 and 203 fall back one after the other to start the sender to transmit the next digit.

Returning now to the point at which the circuit of the stepping magnet 111 of the sequence switch S' was opened at the end of the second code digit, stepping magnet 111, upon deenergizing, advances the wipers 113 and 114 out of engagement with the second set of bank contacts and into engagement with the third set, whereupon wiper 113 grounds the third code digit stop conductor 133. Since only two code digits are needed to trunk the call to the desired office in this case, the third and fourth contacts 310 and 311 in the set of contacts in use are cross-connected by means of the jumpers 314 and 315, respectively, to the skip conductor 316. Accordingly, when the third code digit stop conductor 133 is grounded by wiper 113, a circuit is closed through wiper 306, bank contacts 310, jumper 314, skip conductor 316, and the interrupter contacts 112 for stepping magnet 111 of the sequence switch S' , which thereupon energizes and interrupts its own circuit at contacts 112, whereupon it deenergizes and advances the wipers 113 and 114 another step. Wiper 113 at this time extends ground over the fourth code digit stop conductor 134 to the fourth office register wiper 307, and thence by way of bank contact 311, jumper 315, and skip conductor 316 to stepping magnet 111 by way of interrupter contacts 112. Accordingly, the wipers 113 and 114 are automatically advanced another step and wiper 113 places ground upon the first subscriber digit stop conductor 141.

When the sender is started the third time, as it is following the usual interval after the second digit, it transmits the first subscriber digit, which is registered on the digit register DR^1 . This digit is terminated in the hereinbefore described manner when wiper 236 of the sending switch SS arrives upon the impulse stop conductor upon which wiper 404 of the digit register DR^1 is standing. In case the first subscriber digit is 5 or under, the wipers of the sending switch SS are not advanced beyond the intermediate normal position, and the transmission of the second subscriber digit commences with stop wiper 237 connected up by relay 204, but, if the first subscriber digit is 6 or over, the wipers of the sending switch SS are rotated back to the initial starting position and the transmission of the second subscriber digit starts with the stop wiper 236 connected up by relay 205. At any rate, at the end of the first subscriber digit, the wipers of the sequence switch S' are advanced to ground the second subscriber digit stop conductor 142 to termi-

nate the second subscriber digit, as determined by the setting of the digit register DR^2 . In the same way, the wipers 113 and 114 of the sequence switch S' are advanced at the end of the second subscriber digit, 70 and ground is extended over the third subscriber digit stop conductor 143 to the wiper of the third digit register DR^3 , thereby terminating the third subscriber digit in the usual manner, and, upon the advance of 75 the wipers of the sequence switch S' at the end of the third subscriber digit, ground is extended over the fourth subscriber digit stop conductor 144 to the wipers of the fourth digit register DR^4 , thereby terminating the fourth subscriber digit in the usual manner. 80

At the end of the transmission of the fourth subscriber digit, the wipers 113 and 114 of the sequence switch S' are again advanced in the usual manner and wiper 113 places ground upon conductor 94, thereby closing a circuit through the corresponding contact in the bank of wiper 90 of the director selector DS , wiper 90, working contact and armature 86, and armature 35 and its working contact for switching relay 33 of the trunk circuit TC . Switching relay 33 thereupon energizes; closes a locking circuit for itself at armature 40; and at armatures 39 and 41 disconnects conductors 25 and 27 from the windings of line relay 31 and connects them instead to conductors 42 and 44 extending to the selector D , at the same time disconnecting the control bridge 100 extending to the director, leaving the established connection under the direct control of the calling line. 95

As a result of line relay 31 of the trunk circuit TC being cut off, it deenergizes and 105 opens the circuit of release relay 32 at armature 34. Responsive to this, release relay 32 deenergizes after a slight interval and removes ground from release trunk conductor 43 at armature 36, leaving the said release 110 trunk conductor 43 grounded by way of the release trunk conductor 76 of the trunk comprising conductors 75-77, inclusive.

As a further result of the deenergization of the release relay 32, it opens at armature 115 37 the circuit of switching relay 81 of the director selector DS , whereupon switching relay 81 deenergizes and disconnects the wipers 87-90, inclusive.

In the director, holding relay 201 now deenergizes and places ground on the bank of wiper 114 of the sequence switch S' at armature 117, thereby closing a circuit through the last contact in the bank of wiper 114 for the stepping magnet 111, whereupon stepping magnet 111 energizes and opens its own circuit at contacts 112, thereby deenergizing and advancing the wipers 113 and 114 the remaining step to their normal position. 125 As a further result of the deenergization of 130

relay 201, ground is placed on the release conductor 221 at armature 207. Responsive to this, a circuit is closed through the off normal contacts of each of the release magnets of the digit registers DR¹-DR⁴, inclusive whereupon these digit registers are restored to normal position in the usual manner. For example, release magnet 402 of the digit register DR⁴ energizes through off normal contacts 403 and restores the wiper 404 to normal, whereupon off normal contacts 403 operate and disconnect release magnet 402. In the same way the office register OR, Fig. 4, is restored to normal position by the operation of release magnet 303, and the sequence switch S, Fig. 2, is restored to normal by the operation of release magnet 106. The director is now at normal and is ready to be used in handling another call.

Regarding the established connection, it may be pointed out that the usual train of automatic switches in the called office is operated responsive to the four subscriber digits of the number to complete the connection, whereupon the conversation may be carried on in any desired manner.

When the conversation is terminated, the subscriber at substation A replaces his receiver, whereupon ground is removed from release trunk conductor 76 of the trunk comprising conductors 75-77, inclusive, in the usual manner, whereupon switching relay 55 of the selector D, switching relay 33 of the trunk circuit TC and switching relay 14 of the line switch C, deenergize. Responsive to the deenergization of switching relay 55 of the selector D, a circuit is closed at armature 70 and through armatures 62 and 64 and off normal contacts 57 for release magnet 56, whereupon the wipers of the selector D are restored to normal position in the usual manner.

Referring now again to the sender shown in Fig. 3, it may be well to point out that, as may be seen from the foregoing description, the amount of rotation of the sending switch SS is cut in half by the introduction of the second normal position, i. e., if a digit greater than 5 is called, the sender is obliged to rotate back to the initial starting point, but, if the digit is 4 or under, the wipers of the sending switch are rotated forward to the alternate starting point. On the other hand, if the digit called is 5, the wipers land upon the alternate starting position at the termination of that digit and are not rotated at all.

It will be apparent to those skilled in the art that any one desiring to do so may now provide as many normal positions as may be desirable in any given case. In fact, if so desired, as many normal positions as there are contacts in the bank of the sending switch SS may be provided so that the send-

ing switch SS does not need to rotate forward in any case at the end of a digit, but merely stands where it is last used in all cases, it being understood that there must be a relay similar to relays 204 and 205 for each normal position provided.

What is claimed is:

1. In an impulse sender, contacts for transmitting impulses, a counting switch for counting the impulses as they are transmitted, a stop relay controlled by said counting switch to terminate a series of impulses, two stop wipers for said counting switch for controlling said stop relay, two normal positions for said counting switch, means for starting said switch from either of the two normal positions, and means for connecting up one or the other of said wipers selectively, depending upon which normal position the switch is started from. 75

2. An impulse sender comprising means for sending impulses and a counting switch for counting the impulses as they are transmitted, means for advancing said counting switch step by step in synchronism with the counted impulses, a first normal position for said counting switch, means for starting said counting switch from said first normal position at the beginning of the train of impulses, a second normal position for said switch, means for advancing said switch beyond said second normal position in case the series of impulses is of a predetermined length, and means for stopping said counting switch at said second normal position in case the series of impulses is terminated before said second normal position is passed. 90

3. An impulse sender including a counting switch having two normal positions, means for starting said counting switch from either normal position, and for advancing it beyond the other normal position during the transmission of a series of impulses, and means effective subsequent to the termination of a series of impulses for automatically advancing said counting switch until a normal position is reached and for thereupon stopping said advance. 105

4. An impulse sender including impulse transmitting means, a counting switch for counting impulses, and a stop relay for terminating a series of impulses, said counting switch having a plurality of wipers and a bank of contacts for each wiper, a plurality of normal positions for said switch, a stop relay control wiper for each of said normal positions, a connecting relay for each of said control wipers, and means for automatically energizing the relay corresponding to the instant normal position of said sending switch 115 to connect the said stop relay to the control wiper corresponding to such normal position. 120

5. In an impulse transmitter, a counting switch having two starting positions, means 130

- for operating said switch to count a train of impulses, and means for stopping said switch in one or the other of its starting positions depending on the number of impulses in the train.
6. In an impulse transmitter, a counting switch having a plurality of starting positions, means for operating said switch to count a train of impulses, means for rendering ineffective any starting position reached during the counting of a train of impulses, and means responsive to the completion of the transmission of said train of impulses for automatically continuing the advance of said switch to its nearest starting position.
7. In an impulse transmitter, a counting switch having a plurality of starting positions, a plurality of test wipers in said switch, means for starting said switch from any position, and means for automatically rendering effective the particular test wiper which corresponds to the position from which the switch is started.
8. In a telephone system, a progressively movable multi-position device for counting a group of impulses, said device having a number of start positions, said number being greater than the number of positions on the device divided by the maximum possible number of impulses in the group.
9. In a telephone system, a progressively movable multi-position device for counting a group of impulses, said device having a number of start positions, said number being greater than the number of positions on the device divided by the maximum possible number of impulses in the group, and means for causing any position on the device to correspond to different digits depending upon from which position the device started in its counting action.
10. In a telephone system, a progressively movable multi-position device for counting impulses, and means for causing each position to correspond to any one of a plurality of different digits.
11. In a telephone system, a progressively movable multi-position device for counting impulses, each position corresponding to a plurality of different digits, said device having a plurality of start positions, and means depending upon from which position the device starts to fix the digit corresponding to each position of the device.
12. In a telephone system, a progressively movable device for counting impulses, said device having a plurality of stop positions, and means for rendering ineffective any stop position reached before a count has been completed.
13. In a telephone system, a progressively movable device for counting a predetermined number of impulses, said device having two stop positions, and means for rendering the first stop position to be reached ineffective if the number of impulses is any amount greater than a certain amount.
14. In a telephone system, a progressively movable impulse transmitter wherein there is provided means for initiating the movement of the transmitter to transmit a predetermined number of impulses, and means effective when the impulses have been transmitted for continuing the movement of the transmitter until it reaches a stop position but rendering it ineffective to transmit additional impulses, characterized in this, that the transmitter is provided with a plurality of stop positions each of which may be reached during the impulse transmitting movement of the transmitter, and means whereby those positions are rendered ineffective until the last named means has operated.
15. In a telephone system, an impulse transmitter including means for transmitting impulses and a counting switch for counting the impulses as they are transmitted, said counting switch having a plurality of normal stopping positions, means for starting said counting switch from any normal position at the beginning of the train of impulses, means for advancing said switch beyond a succeeding normal position in case the number of impulses is greater than a predetermined number, and means for stopping said counting switch at a succeeding position in case the number of impulses is not greater than that predetermined number.
16. In a telephone system, a counting device for counting groups of impulses, said device having a number of stop positions, means for rendering any stop position ineffective, and means for commencing counting from any of said stop positions.
17. In a telephone system, a counting device for counting a group of impulses, said device having a number of stop positions, means dependent upon the number of impulses counted for determining in which position the switch will stop, and means for commencing the subsequent operation of the switch from the preceding stop position.
18. In a telephone system, a device for counting a number of impulses, said device having two stop positions, and means for stopping said device in one of said positions if the number of impulses counted is not more than a certain number and in the other position if it is more than said number.
19. In a telephone system, a progressively movable multi-position device for transmitting impulses, and means for rendering any one of certain of the positions a stop position depending upon which position was the last stop position and the number of impulses that are transmitted.
- In witness whereof, I hereunto subscribe my name this 6th day of June, A. D. 1924.

RUDOLPH F. STEHLIK.
